UNITED STATES PATENT OFFICE.

OSCAR A. WEISSENBORN, OF JERSEY CITY, NEW JERSEY.

SAFE.

SPECIFICATION forming part of Letters Patent No. 674,145, dated May 14, 1901.

Application filed October 18, 1900. Serial No. 33,446. (No model.)

To all whom it may concern:

Be it known that I, OSCAR A. WEISSENBORN, a citizen of the United States, residing at Jersey City, in the county of Hudson and State 5 of New Jersey, have invented certain new and useful Improvements in Safes, of which the following is a specification.

The invention relates to a safe for the use of families and householders and in other situations for the safe keeping of important papers and documents, costly jewelry, and other valuables.

The object and purpose is to improve the construction so as to materially reduce the 15 cost while maintaining the required security, and at the same time so facilitate the transportation of the safe that it may be removed when necessary by simple manual labor without the use of machinery.

20 The general construction of a safe is that of two divisions—a burglar-proof and a fire-proof division—one placed within and removable from the other. The burglar-proof security is against ordinary looting of a dwelling, and the fireproofing is designed to resist the degree and continuance of heat encountered in burning of a house. Means are also provided to guard against the theft and removal of the safe.

25 To enable others skilled in the art to make and use my invention, I will proceed to describe the same, referring to the annexed drawings, which show a safe embodying my improvements.

30 In said drawings, Figure 1 is a vertical transverse section giving a general view of the construction preferred in carrying my invention into practice; and Fig. 2 is a perspective view, reduced, of the inner parts detached.

35 Referring to Fig. 1, A indicates the main body or outer portion of the safe, consisting of a metallic box, preferably of very hard iron or steel, made to resist fracture by blows of a hammer and proof against the action of 40 an ordinary drill. Within this box A is a detachable section B, herein called the "primary inner section," composed of two shells, forming a double-walled box and containing between the walls the fireproofing material

45 b. This section is thus complete in itself and separable from the outer box, so that when desired to remove the safe the inner section

may be lifted out, and so permitting the safe to be moved in pieces. The body A has a door or cover a', carrying a mass b of the said 55 filling. The safe is provided with proper locks and bolts, but none are shown because not a part of my invention.

In order to prevent the clandestine removal of the safe, I employ a device for fastening 60 the safe permanently to the building where used. Such device is here represented by lag-screws S S, to be screwed into the wall or floor, as f, and, if desired, may take the form of bolts, as h, made long enough to pass 65 through a beam of the house, as g, and receive a nut on the opposite side. The bottom or floor c of the body A is preferably of extra thickness and is perforated to receive the said screws or bolts, the heads being let into the floor 70 c below its surface and the cavity above the heads filled with cement to cover the heads. The fastening device is protected from being tampered with by the primary inner section B, which is withdrawn from the outer section 75 when the safe is to be made fast and afterward reinserted. As the door is closed and locked upon the inner section the fastening device becomes inaccessible to any except the owner or person holding the safe-key or the 80 "combination," if a permutation-lock. To allow the inner section to be easily detached from the outer box, the lines of separation are slightly inclined inward, as indicated in Fig. 1. 85

The contents of the safe are placed in a cabinet or case C, consisting of a secondary inner section, which is again divided into two parts k and l, adapted to slide into the interior of primary section B. The part l is of 90 less depth than the interior of B and rests on cleats s' therein to form a secret chamber e beneath it. Likewise the inner part k is made shallower than l and has a cleat k' fixed to its upper edge, whereby it is prevented 95 from passing inward, and so leaves a space e' for another secret chamber. No access to these secret spaces can be had by the door alone, but the cabinet must be drawn out bodily, as by knobs O, having screws by which 100 to connect its two parts.

The above-described fire and burglar proof safe embodies improvements whereby security is maintained and the cost is so reduced

as to enable any family of moderate means to possess a convenient lockup for valuables, and at the same time the sectional structure admits of easy transportation, as the safe can 5 be taken in pieces, removed, and set up again by hand and without the use of skilled labor or machinery.

The said improvements are not restricted to particular forms or special construction, as 10 the same may be varied within the invention. I have shown the burglar-proof part as exterior and the fireproof within; but the order may be reversed and the exterior portion made fireproof.

15 I claim as my invention—

1. In a sectional fire and burglar proof safe, the combination with a drill-resisting outer section or box as A, of a removable primary section, made with double walls containing 20 fireproof material between the walls, and closed by a double-walled fireproof safe-door, and a secondary section or cabinet within the primary section constructed to conceal a se-

cret compartment between it and the fireproof section, which is accessible only by removing 25 such inner section or cabinet, after first unfastening and opening the safe-door.

2. In a safe comprising fire and burglar proof inner and outer sections, the combination with a drill-resisting outer section or box 30 as A, containing means of fastening the safe to the building where used, of a double-walled primary inner section inclosing a secondary inner section made in two parts, as described, such primary section containing fire-resisting 35 material arranged to cover and conceal the fastening means aforesaid, and the two parts of the secondary inner section constructed to inclose one or more secret compartments between them which are inaccessible without re- 40 moving a section of the safe.

OSCAR A. WEISSENBORN.
